UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

THREAD-PARTING MECHANISM FOR WEFT-REPLENISHING LOOMS.

Application filed February 25, 1919. Serial No. 279,096.

To all whom it may concern:

Be it known that I, JONAS NORTHRUP, a citizen of the United States, residing at Hopedale, in the county of Worcester and 5 State of Massachusetts, have invented certain new and useful Improvements in Thread-Parting Mechanism for Weft-Replenishing Looms; and I do hereby declare the following to be a full, clear, and exact 10 description of the invention, such as will enable others skilled in the art to which it appertains to make and use the same.

The present invention relates to an improvement in thread parting mechanism for 15 weft replenishing looms. The object of the invention is to produce an improved thread parting mechanism for looms operating when the filling on the bobbin or filling carrier has been exhausted to a predetermined extent and the bobbin is about to be 20 ejected from the shuttle, to sever it near the shuttle and afterward close to the selvage. The parting devices forming the subject of this invention, are mounted on the shuttle feeler and operated by connections with the weft replenishing mechanism and while 25 of such construction and arrangement as to be adapted for embodiment in new looms, are particularly adapted for application to old looms, and to these ends the invention 30 consists of the mechanism hereinafter described and claimed.

In the accompanying drawings illustrating 35 the preferred embodiment of the invention, Figure 1 is a side elevation of the hopper and associated parts of the weft replenishing loom showing the application of the thread parting mechanism thereto; Figs. 2 and 3 are enlarged elevations and bottom 40 plans respectively of the cutter mechanism mounted on the lower end of the shuttle feeler; Fig. 4 is a side elevation similar to Fig. 1 showing the parts in position when replenishment has been indicated; Fig. 5 is 45 a plan of the same; Fig. 6 is a detail showing a portion of the cutter opening means; Fig. 7 is a side elevation similar to Fig. 1 illustrating the parts in the position they assume when cutting has just been completed; Fig. 8 is a plan showing the relation 50 of the cutting devices to the shuttle, cloth and temple; and Fig. 9 is a perspective view of a slot block hereinafter referred to.

In the illustrated embodiment of the in-

vention, the improved thread parting mechanism is shown as mounted upon a feeler-controlled weft replenishing loom. The parts of the weft replenishing mechanism necessary for the operation of the thread parting mechanism consist of a hopper 10 mounted upon the bracket 11 secured to the breast beam 12; the hopper arm 13 is mounted upon a rock shaft 14 which extends along the front side of the loom and is connected at the other end with the filling feeler mechanism. Mounted upon the trans- 55 ferrer stud 15 is an arm 16 connected by means of the link 17 with the shuttle feeler 18 which is mounted upon a stud 19 secured to the hopper plate 10. The shuttle feeler 18 operates in the usual well known manner. When a fresh supply of filling is to be inserted in the shuttle the hopper arm 13 moves from the position shown in Fig. 1 to the position shown in Fig. 4 drawing 60 70 with it the arm 16 to which it is connected by means of the spring 20, and thereupon the shuttle feeler is swung rearwardly or 75 toward the left, as shown in Fig. 4.

The thread parting mechanism is mounted 80 upon the shuttle feeler and when a change of filling has been indicated and the lay 22 moves forward with the shuttle 23 correctly boxed, the thread parting means 85 is actuated to sever and hold the old filling extending from the selvage to the shuttle.

The thread parting means comprises a movable knife and associated parts for supporting it in position on the shuttle feeler, 90 means for opening the knife when replenishment is indicated, also mounted on the feeler and actuated from the hopper arm, and a parter actuating device mounted on the lay adapted to cause the knife to sever and hold the thread.

The parting and holding means and the actuating devices therefor are described as follows:—

The lower end 30 of the shuttle feeler 18 carries the knife 31 pivoted on the pin 36. 100 The bolt 32 passes through the slot 73 in the knife 31, whereby the knife is free to be swung on its pivot 36. The knife has a cutting edge at 33 which cooperates with a steel cutting plate 34 received in a recess in the side of the lower end 30 of the shuttle feeler. The knife and cutting plate 105 operate in scissors fashion. When the cut-

ting plate becomes worn it may be turned end for end. On the opposite side of the knife 31 from the feeler end 30 is a knife holding plate 35 which is also supported on the bolt 32. This knife holding plate 35 is provided with two pins 36 and 37 which project laterally from it and enter two holes in the cover plate 38. A washer 40 on the bolt 32 engages the side of the holding plate 35 and is pressed against such plate by a spring washer 41 also mounted on the bolt 32 between the washer 40 and the cover plate 38. This washer 40 is cut away at 42. A spring 43 is mounted on the post 36. It has one end 44 which engages a notch in the cover plate 38, and another end which extends downwardly alongside of the knife holding plate 35, and thence rearwardly and upwardly and is bent back upon itself, as shown in Fig. 2. The flexible thread guide 43 serves to guide the thread to the parting means and also to cushion the impact of the shuttle feeler against either the shuttle or the shuttle box, and yields upwardly upon contact therewith, to permit the shuttle feeler to properly perform its shuttle feeling function. The position of the pin 36 and the sides of the washer 40 are such that the cut-away portion 42 of the washer leaves room between the edge of the washer and the pin 36. It will thus be seen that the knife is yieldingly held between the side of the feeler arm and the knife holding plate 35 by the resilient pressure of the spring washer 41, and that while the knife may be moved easily under such pressure the latter is sufficient to hold the knife in any given position to which it may be moved. The upper end of the knife 31 carries a striker block 50 which is rigidly secured to the knife. From the side of the block there projects the pin 51 which is adapted to be engaged by the knife opening devices hereinafter referred to. The block 50 is adapted to be struck by the knife actuating tappet 52 adjustably mounted by means of a screw 53 and slot 55 on the shuttle box top 54.

50 The knife opening device consists of the arm 60 pivotally mounted at 61 on a projection 62 from the side of the shuttle feeler arm 18. Pivotally mounted on the lower end of the lever 60 is the by-pass pawl 63 held by the spring 64 to the position shown in Fig. 1. The by-pass pawl 63 has a laterally extended tail 65 which engages the side of the arm 60, as shown in Fig. 6. The pivot for the arm 60 consists of a right angle portion 66 of the arm 67 which arm 67 passes through a hole in the projection 62 and has the arm 60 rigidly secured to it by means of two set screws 69 and 70. The upper end of the arm 67 is bent around 65 to form an opening for the link 71 which

connects it with the hopper arm 13, the forward end of the link being bent at right angles to the shank thereof, passing through a slot 75 in the head-piece 76 secured on the upper end of the hopper arm. When the hopper arm is moved to the right from the position shown in Fig. 1 to the position shown in Fig. 4, the end of the slot 75 engages the bent end of the link 71 and pulls upon the link, thereby turning the arm 60 and moving the bypass pawl 63 toward the pin 51 on the knife block. The pawl thereby moves the knife in the direction to open it to the position shown in Figs. 2 and 4, and passes over the pin 51. At the same time the shuttle feeler is rocked through the medium of the link 17 and turned upon its pivot from the position shown in Fig. 1 to the position shown in Fig. 4. Then, as the lay beats up the yarn extending from the selvage, the filling enters the open mouth of the knife and at the extremity of the beat the tappet 52 strikes the knife block 50 and actuates the latter to cause it to cut the yarn. As the yarn is cut the end extending to the selvage is gripped between the side of the knife and the knife holding plate 35 so as thereby to hold the yarn extending from the cutter to the selvage. On the back stroke of the hopper arm the knife opening arm is oscillated in the opposite direction but the by-pass pawl rides over the knife pin 51 without any effect upon the knife itself, leaving the knife standing closed in its initial position ready for a repetition of the operations. The length of the slot 75 in the hopper arm casting 76 is regulated by means of the slot block 80 which is shown in perspective in Fig. 9 and has a square projection which enters the slot 75 in which it is secured in adjusted position by means of a bolt 81. The position of the block regulates the time of retraction of the knife opening device. It will thus be observed that the knife is positively opened by the knife opening device regardless of the exact position or movement of the shuttle feeler or of the tension of the actuating spring 20.

55 The shuttle feeler is mounted on the stud 19 so that it may slide longitudinally thereof, the feeler being provided with an upwardly extending cam arm 90 which engages a slot 91 in the bracket 92 supported on the hopper plate 10. When the feeler is standing in its normal position, as shown in Fig. 1, the cam arm 90 occupies a position at the rear end of the slot 91. When the shuttle feeler swings rearward into the position shown in Fig. 4 ready to engage a misplaced shuttle, or to sever the thread from a correctly boxed shuttle, then the cam arm 90 occupies the position shown in Fig. 5 at the forward end of the slot 91.

60 The slot 91 is an angular slot, as shown in 115

120

125

130

- Fig. 5, and is designed so that the movement of the cam arm 90 from the position shown in Fig. 5 to the other end of the slot 91, causes the shuttle feeler to move longitudinally on the stud 19 as it is oscillated thereon. The result of the combination of these two movements upon the thread parting mechanism is to cause the latter to move in such a path that the filling thread held thereby is relieved from excessive tension when the thread parting mechanism moves from the full line to the dotted line position as shown in Fig. 8, and consequently danger of breakage is eliminated.
- 15 In this manner the filling thread is held out of the path of the lay so that this loose end may not be caught up and woven into the cloth, and furthermore this loose end of filling thread is retained in this position until the thread parter 56 connected with the loom temple severs the thread close beside the selvage. Upon the repetition of the cycle of movements as above described wherein the hopper arm moves from the position shown in Fig. 1 to that shown in Fig. 4, the knife 31 opens, thus releasing the severed thread whereupon it drops out of the way, and accordingly the thread parting mechanism is placed in an operative position with the knife open, ready to receive and cut the filling thread from the next bobbin.
- From the foregoing description of the preferred embodiment of my invention it will be observed that the movable thread parting device serves the double function of cutting the filling thread near the shuttle when replenishment is indicated and also of gripping the portion thereof which extends to the selvage and holding the same during movement away from the shuttle and out of the range of the operation of the lay. The path of movement of the thread parting mechanism is such that additional tension on this portion of the thread is avoided, whereby all danger of breakage thereof is eliminated and furthermore in this manner the thread is conveniently presented to the cutting member 56 to be cut at a point near the selvage.
- It is also to be observed that the present invention contemplates a construction wherein in a shuttle feeler, thread parting, thread holding mechanism, and parter operating means are adapted to be assembled as a unit, and applied to a loom as such. It is obvious that such construction is of immense practical value both in assembling a loom, and in installing the devices on an assembled loom. In the former instance the various devices are coordinated to the end that when the unit is established in its proper place, each device will be properly related to and will operate in conjunction with the other devices of the unit, so that the amount of time consumed in regulating the operation thereof will be a minimum. In the latter case, the

unit may be readily assembled by the manufacturer at his plant, shipped to the loom at another plant, and installed thereon by comparatively unskilled labor, and in this case also after the installation of the unit, the various devices will operate in a perfectly timed manner.

Having thus described my invention what I claim is:—

1. A weft replenishing loom having, in combination, a bobbin changing mechanism, a lay, a shuttle feeler having a thread parting mechanism mounted thereon provided with a cutting knife having provision to be opened to engage the filling thread by the bobbin changing mechanism when replenishment is indicated independently of movement of the shuttle feeler, an actuating device mounted on the lay for actuating the thread parting mechanism to cause the knife to sever and to hold the filling thread. 75

2. A thread parting mechanism having, in combination, a shuttle feeler, a movable knife pivoted thereon, a cutting plate cooperating with the knife, a knife holding plate, a spring washer cooperating with the holding plate to yieldingly hold the knife in any position to which it may be moved, a by pass pawl carried by the shuttle feeler adapted to engage the knife upon movement of the shuttle feeler in one direction and to ride over the knife on the return movement to permit same to remain closed. 90

3. A weft replenishing loom having, in combination, a movable hopper arm, a shuttle feeler, a thread parting mechanism provided with a knife pivoted on the shuttle feeler means carried by the shuttle feeler and operatively connected with the hopper arm to open the knife to engage the thread 105 when the hopper arm moves in one direction, a lay adapted to engage the knife to close the same and sever the thread. 100

4. A weft replenishing loom having, in combination, a movable hopper arm, a shuttle feeler, a thread parting mechanism provided with a knife pivoted on the shuttle feeler and operatively connected with the hopper arm to open the knife to engage the thread 110 when the hopper arm moves in one direction, and to have no effect upon movement of the knife when the hopper arm moves in the other direction. 115

5. A weft replenishing loom having, in combination, a hopper arm, a shuttle feeler yieldingly connected with the hopper arm, a thread parter comprising cutter blades mounted on the shuttle feeler, and means for opening the blades independently of the movement of the shuttle feeler. 125

6. A weft replenishing loom having, in combination, a bobbin changing mechanism, a shuttle, a shuttle feeler, a cutting mechanism movable to and from the shuttle, and provided with a knife operatively con- 130

nected with the bobbin changing mechanism, and arranged to be opened thereby independently of movement of the shuttle feeler, to sever the thread near the shuttle when 5 replenishment is indicated and to hold the portion thereof extending to the selvage during movement thereof away from the shuttle.

7. A weft replenishing loom having, in combination, a shuttle, a hopper arm, a shuttle feeler, a cutting mechanism located near the selvage, a second cutting mechanism mounted upon the shuttle feeler for severing the thread near the shuttle, and connections between the second cutting mechanism and hopper arm by which the cutting mechanism is prepared to cut the thread upon movement of the hopper arm, the operation of said cutting mechanism being thereby rendered independent of the movements of the 20 shuttle feeler.

8. A weft replenishing loom having, in combination, a movable hopper arm, a thread parting mechanism provided with a movable knife, means for opening the knife 25 adjustably connected with the hopper arm to permit the timing thereof with relation to the movement of the hopper arm said knife opening means being operated independently of the shuttle feeler.

30 9. A weft replenishing loom having, in combination, a weft replenishing mechanism, a movable hopper arm actuated thereby, a pivot, a shuttle feeler oscillated about the pivot by the hopper arm, means cooper- 35 ating with the shuttle feeler to move the

same longitudinally of the pivot as it oscillates thereon, a thread parting mechanism carried by the shuttle feeler and having a movable knife, means actuated by the hopper 40 arm to open the knife to engage the thread and a lay cooperating with the thread parting mechanism to close the knife and sever the thread.

10. A weft replenishing loom having, in combination, weft replenishing mechanism 45 including a hopper plate, a pivoted shuttle feeler, a thread cutter provided with a movable knife, a thread holder, and knife opening means actuated by the weft replenishing mechanism independently of the movements of the shuttle feeler, the shuttle feeler, thread cutter, thread holder and knife opening means being mounted on the hopper plate.

11. A weft replenishing loom having, in 55 combination, a hopper, a shuttle feeler mounted thereon, a thread cutting and holding device carried by the shuttle feeler, and a cam mounted on the hopper and cooperating with the shuttle feeler to release the tension on the filling when the latter has been engaged by the thread cutting and holding device.

12. A weft replenishing loom having, in 60 combination, a hopper plate, a shuttle feeler pivoted directly on the hopper plate, thread parting means, thread holding means, and parter operating means being mounted on the feeler.

JONAS NORTHRUP.
